W. H. H. HINDS.

Lamp Extinguisher.

No. 64,671.

Patented May 14, 1867.

Inventor:

William H. H. Hinds,

United States Patent Office.

WILLIAM H. H. HINDS, OF GROTON, MASSACHUSETTS.

Letters Patent No. 64,671, dated May 14, 1867; antedated May 6, 1867.

FLAME REGULATOR AND EXTINGUISHER FOR LAMPS.

The Schedule referred to in these Letters Patent and making part of the same.

TO ALL WHOM IT MAY CONCERN:

Be it known that I, WILLIAM H. H. HINDS, of the town of Groton, in the county of Middlesex, in the State of Massachusetts, have invented a new and improved Mode of Regulating and Extinguishing Flames for giving light; and I do hereby declare that the following is a full and exact description thereof, reference being had to the accompanying drawings, and to the letters of reference marked thereon.

The nature of my invention consists in attaching two pieces of metal, made to close together around or above the flame, to a cap, to which cap is attached a collar or chimney-holder, when a chimney is used, in such a manner that the said two pieces of metal shall form the vertex or top, or a part of the vertex or top of said cap. Said two pieces of metal to conform to the shape of the top of said cap. For a flat wick, the vertex or top of said cap should be convex or rounding. For a wick of any other form, the vertex or top of said cap should be flat or nearly so. The whole to be made of suitable metal.

Figure 1 is a side view of a lamp with my flame regulator and extinguisher attached. C C is the cap, to which are attached, a, the two pieces of metal encircling the flame. Said two pieces of metal are attached to the cap C C by means of two pivots d d, passing through the two ends of said two pieces of metal, uniting them together and to said cap. Said two pieces of metal are made to close and open by the opposite end of each being connected or attached to the collar or chimney-holder b b, which is made to revolve from left to right, and right to left, or *vice versa*, sufficiently for the purpose. When the top of the cap C C is flat, or nearly so, the said two pieces of metal are not united, but attached severally or singly to said cap, as above described, and made to close and open as above described. l shows a hole in the cap C C for the purpose of adjusting the wick without removing said cap, when said flame regulator and extinguisher is used on a lamp without a ratchet. ff is a platform or bottom for the cap C C to rest on, and is attached to the tube g, shown in fig. 3, when said flame regulator and extinguisher is used on a lamp. i i is a metallic ring attached to the neck or body of the lamp, and supporting the tube g containing the wick, as shown in fig. 3, when the tube g and metallic ring i i are screwed together.

Figure 2 is a transverse sectional view through the centre of said flame regulator and extinguisher. a is one of the said two pieces of metal; d d the pivots that connect it with the cap C C. b b is the collar or chimney-holder, showing its connection with the two pieces of metal a. C C is the cap to which the two pieces of metal a encircling the flame are attached by the pivots d d. E E and e e are the slide and its support to hold the cap C C in position. The support e e may be made of perforated metal, or in any other way to give a free circulation of air. o o o o o o o o o o o o are air-holes.

Figure 3 is transverse sectional view through the centre of a lamp wick-tube and platform or bottom.

Figure 4 is a bottom view of the slide E E and its support e e that hold the cap C C in position; also of a part of the inside of the caps C C below e e.

By the above device I have a new and improved regulator and extinguisher of flames for giving light, adapted to a flat or a wick of any other form, giving more light from the same amount of burning material, and much less liable to explosion, as it prevents the contents of the lamp from heating.

What I claim as my invention, and desire to secure by Letters Patent, is—

1. The attaching of two pieces of metal, made to close together around or above the flame, to a cap, to which cap is attached a collar or chimney-holder when a chimney is used, in such a manner that the said two pieces of metal shall form the vertex or top, or a part of the vertex or top of said cap, as herein described, and as shown in figs. 1 and 2.
2. The closing and opening of the said two pieces of metal by means of a collar or chimney-holder, as herein described, and as shown in figs. 1 and 2.

WM. H. H. HINDS.
